(57) CLAIM

The ornamental design for a built-in home appliance, as shown and described.

DESCRIPTION

FIG. 1 is a front perspective view of a built-in home appliance showing our new design;
 FIG. 2 is a front view thereof;
 FIG. 3 is a rear view thereof;
 FIG. 4 is a top view thereof;
 FIG. 5 is a bottom view thereof;
 FIG. 6 is a right side view thereof; and,
 FIG. 7 is a left side view thereof.

The broken line showing is included for the purpose of illustrating unclaimed subject matter and forms no part of the claimed design.
